UNITED STATES PATENT OFFICE.

CHRISTIAN G. SINGLEY, OF MANHEIM, PENNSYLVANIA.

DESIGN FOR A CIGAR OR SIMILAR ARTICLE.

SPECIFICATION forming part of Design No. 28,786, dated June 7, 1898.

Application filed February 26, 1898. Serial No. 671,861. Term of patent 7 years.

To all whom it may concern:

Be it known that I, CHRISTIAN G. SINGLEY, a citizen of the United States, residing at Manheim, in the county of Lancaster, State of Pennsylvania, have invented and produced a new and original Design for Cigars or Similar Articles, of which the following is a specification, reference being had to the accompanying drawing, forming part thereof.

10 The figure of the drawing shows a side view of my new design.

This invention has relation to a certain new and original design for cigars or similar articles; and it consists in the novel form and 15 configuration thereof, all as hereinafter described, and illustrated in the accompanying drawing.

The leading feature of this design consists of a cigar having the tuck end thereof turned or set at an approximate right angle with the 20 head end thereof, the angle being formed at about the center of the cigar.

In the drawing, A designates the tuck of the cigar, B the head, and D the angle formed between the tuck and the head.

Having described my invention, what I claim as new, and desire to secure by Letters Patent, is—

The design for a cigar, or similar article, substantially as herein shown and described. 25 30
